US0D1022666S

(12) **United States Design Patent** (10) Patent No.: **US D1,022,666 S**
(45) Date of Patent: ** Apr. 16, 2024

(54) **MOUNTING DEVICE FOR FLOOR PANELS**

(71) Applicant: **Surface Technologies GmbH & Co. KG**, Baruth (DE)

(72) Inventor: **Erich Schäfers**, Oberkail (DE)

(**) Term: **15 Years**

(21) Appl. No.: **35/515,955**

(22) Filed: **Jun. 9, 2022**

(80) **Hague Agreement Data**

Int. Filing Date: **Jun. 9, 2022**

Int. Reg. No.: **DM/222395**

Int. Reg. Date: **Jun. 9, 2022**

Int. Reg. Pub. Date: **Jan. 13, 2023**

(30) **Foreign Application Priority Data**

Dec. 30, 2021 (DE) 20 2021 003 901.5

(51) LOC (14) Cl. **08-05**

(52) U.S. Cl.

USPC **D8/349**

(57) **CLAIM**

The ornamental design for a mounting device for floor panels, as shown and described.

DESCRIPTION

1. Mounting device for floor panels

2. Mounting device for floor panels

3. Mounting device for floor panels

4. Mounting device for floor panels

1.1 : Right

1.2 : Left

1.3 : Top

1.4 : Bottom

1.5 : Front

1.6 : Back

1.7 : Perspective

2.1 : Right

2.2 : Left

2.4 : Bottom

2.5 : Front

2.6 : Back

2.7 : Perspective

3.1 : Right

3.2 : Left

3.3 : Top

3.4 : Bottom

3.5 : Front

3.6 : Back

3.7 : Perspective

4.1 : Right

4.2 : Left

4.3 : Top

4.4 : Bottom

4.5 : Front

4.6 : Back

4.7 : Perspective

Design 1 and 3: mounting device for locking adjacent floor panels: the mounting device includes a first portion having three downward directed legs and a second portion having a longitudinally extending member oriented relatively perpendicular to the first portion; design 2 and 4: mounting device for locking adjacent floor panels; the mounting device includes a first portion having two downward directed legs

(Continued)

and a second portion having a longitudinally extending member oriented relatively perpendicular to the first portion.
